PHOTOGRAPH HOLDING CHARM

Dollie A. De Fleece, Bronx, N. Y.

Application September 28, 1950, Serial No. 12,380

Term of patent 14 years

(Cl. D45—17)

To all whom it may concern:

Be it known that I, Dollie A. De Fleece, a citizen of the United States, residing at 2171 Quimby Avenue, Bronx, New York, have invented a new, original, and ornamental Design for a Photograph Holding Charm, of which the following is a specification, reference being had to the accompanying drawing, constituting a part hereof.

Figs. 1 and 2 are front and rear perspective views, respectively, of a photograph holding charm embodying my new design;

Fig. 3 is a front elevation of the photograph holding charm; and

Fig. 4 is a side elevational view thereof.

I claim:

The ornamental design for a photograph holding charm, substantially as shown.

DOLLIE A. DE FLEECE.
